UNITED STATES PATENT OFFICE.

JAMES L. DICKSON, OF CHINOOK, MONTANA.

ARTIFICIAL DENTURE.

Application filed December 28, 1921. Serial No. 525,417.

To all whom it may concern:

Be it known that I, JAMES L. DICKSON, a citizen of the United States, residing at Chinook, in the county of Blaine and State 5 of Montana, have invented a new and useful Artificial Denture, of which the following is a specification.

This invention relates to a means for repairing the artificial teeth of a dental plate.

10 The object of the invention is the provision of an improved means for readily and quickly replacing or repairing broken artificial teeth in a plate without injury to the latter, the securing means for such teeth being provided with a head or enlargement and shaped to permit of its being turned by a tool, that portion of the securing means which is engaged by the tool being subsequently sheared or filed off in any approved 15 manner, flush with the outer surface of the tooth, so as to present in appearance a filling for the latter.

The invention will be best understood from a consideration of the following detailed description taken in connection with the accompanying drawing forming part of this specification, with the understanding, however, that the invention is not confined to any strict conformity with the showing 25 in the drawing, but may be changed and modified so long as such changes and modifications mark no material departure from the salient features of the invention as expressed in the appended claim.

30 In the drawings:—

Fig. 1 is a view in perspective of a dental plate, disclosing several artificial teeth secured by my improved means to the plate.

Fig. 2 is a bottom plan view of the same.

40 Fig. 3 is a detail view in cross section, showing the securing means disposed transversely of a tooth for holding a tooth to the plate.

Fig. 4 is a like view with part of the head 45 of the securing means filed or ground off flush with the tooth and disclosing the finished product.

Fig. 5 is a detail view in cross section, disclosing a tooth secured to the plate, with the 50 securing means disposed longitudinally of the tooth.

Referring to the drawing, 1 designates a plate formed of rubber, or metal, or any composition suitable for the purpose, having 55 the upwardly-extended flanged portion 2 which simulates the gums, and provided

with sockets 3, in which are seated any one of the artificial teeth 4. As shown in Figs. 1 and 2, the upper plate is disclosed provided with a full row of artificial teeth, with 60 certain of the teeth fastened to the plate by my improved method.

Should any of the teeth become broken or need replacement, my invention is used for repairing or replacing the teeth. It consists 65

in providing a passage either laterally or longitudinally of the artificial teeth, then forming a threaded opening in the plate in alinement with the passage in the teeth. The teeth are secured within the sockets 3 of the 70

plate by inserting an anchor screw 5 through the passage 6 in the tooth and into the threaded opening in the plate, so that as the screw is manipulated, the threaded portion 75

of the screw will engage the threaded opening in the plate and draw the tooth up securely within the socket 3. The head 8 of the screw is of such a formation that it will be seated snugly within a countersunk portion 80

9 formed at the mouth of the opening 6 in the tooth 4 and clamp the tooth in position within the socket 3 in the plate. The portion of the head 8 which projects beyond the outer surface of the tooth 4 is provided 85

with a slot or nick 10 adapted to be engaged by a suitable tool, such as a screw driver, for turning the screw. The portion of the head 8 of the screw which extends beyond the outer surface of the tooth 4 is adapted 90

to be sheared, filed, or ground off in any approved manner, so that the portion of the head of the screw which remains seated in the socket will disclose an outer surface 11 flush with the outer surface of the tooth 4, 95 which will present the appearance of a filling for the tooth (Fig. 4). The screw 5 in such case may be made of any precious metal, such as gold or the like.

By this securing means, no cement of any kind is required for cementing the tooth in the socket, and the ugly appearing head of the screw is eliminated. The screw 5 provides a very reliable means for positioning artificial teeth in place as shown in Figs. 3 and 4, and whereby the tooth may be readily 100 removed upon the removal of the screw.

The screw 5 may be passed laterally or longitudinally through the tooth, as will appear from the constructions disclosed in Figs. 3 and 5. In Fig. 3, the tooth is provided with a lateral passage, while in Fig. 5, the screw is inserted through a longitudu- 110

dinal passage, and the head 8 is ground off in the same manner as are the heads of the laterally inserted screws shown in Fig. 4. In either case, the ground surface of the head of the screw presents the appearance of either a gold or silver filling, as the case may be, depending upon the metal used for forming the screw.

In the construction shown in Fig. 5, the sheared-off head will be located in the crown of the tooth instead of in the side surface of the teeth, as disclosed in Figs. 3 and 4.

A sufficient portion of the head remains seated within the countersunk portion or socket 9 formed at the mouth of the passage 6 to firmly clamp the tooth in position on the dental plate.

What is claimed is:—

20 A means for repairing the teeth of an artificial denture wherein the plate is pro-

vided with sockets for the reception of the teeth, consisting of an artificial tooth provided with a passage therethrough, and a screw-threaded opening in the wall of the 25 socket which is adapted to be alined with the passage in the tooth, said passage having a countersunk portion at its mouth, and a screw provided with a head inserted through the passage of the tooth and screwed into the 30 threaded opening in the plate, a portion of the head of the screw being seated in and filling the countersunk portion of said passage, the extended portion of the head being ground off flush with the surface of the 35 tooth, whereby the ground off surface of the head presents the appearance of a filling for the tooth.

In testimony, that I claim the foregoing as my own, I have hereto affixed my signature.

JAMES L. DICKSON.
